DESIGN FOR A WHISTLE

Thomas F. Butterfield, Watertown, Conn., assignor to Field Manufacturing Company, Inc., New York, N. Y., a corporation of New York

Application October 22, 1935, Serial No. 59,172

Term of patent 14 years

To all whom it may concern:

Be it known that I, Thomas F. Butterfield, a citizen of the United States and residing at Watertown, county of Litchfield and State of Connecticut, have invented a new, original, and ornamental Design for Whistles, of which the following is a specification, reference being had to the accompanying drawing, forming part thereof:

Fig. 1 is a top perspective view of a whistle, showing my new design; and

Fig. 2 is a bottom perspective view thereof.

I claim:

The ornamental design for a whistle as shown.

THOMAS F. BUTTERFIELD.
